(57) **CLAIM**

The ornamental design for a tennis racket frame, as shown and described.

DESCRIPTION

FIG. 1 is a front elevation view of a first embodiment of a tennis racket frame showing our new design, the rear elevation view thereof being the same;

FIG. 2 is a top plan view thereof;

FIG. 3 is a bottom plan view thereof;

FIG. 4 is a left side elevation view thereof, the right side elevation view thereof being the same;

FIG. 5 is a partial enlarged view of the portion 5-5 in FIG. 1;

FIG. 6 is a cross-sectional view taken along the line 6-6 in FIG. 5;

FIG. 7 is a partial enlarged view of the portion 7-7 in FIG. 6;

FIG. 8 is a partial enlarged cross-sectional view taken along the line 8-8 of FIG. 7;

FIG. 9 is a front elevation view of a second embodiment of a tennis racket frame showing our new design, the rear elevation view thereof being the same;

FIG. 10 is a top plan view thereof;

FIG. 11 is a bottom plan view thereof;

FIG. 12 is a left side elevation view thereof, the right side elevation view thereof being the same;

FIG. 13 is a partial enlarged view of the portion 13-13 in FIG. 9;

FIG. 14 is a cross-sectional view taken along the line 14-14 in FIG. 13;

FIG. 15 is a partial enlarged view of the portion 15-15 in FIG. 14;

FIG. 16 is a partial enlarged cross-sectional view taken along the line 16-16 of FIG. 15;

FIG. 17 is a front elevation view of a third embodiment of a tennis racket frame showing our new design, the rear elevation view thereof being the same;

FIG. 18 is a top plan view thereof;

(Continued)

FIG. 19 is a bottom plan view thereof;
 FIG. 20 is a left side elevation view thereof, the right side elevation view thereof being the same;
 FIG. 21 is a partial enlarged view of the portion 21-21 in FIG. 17;
 FIG. 22 is a cross-sectional view taken along the line 22-22 in FIG. 21;
 FIG. 23 is a partial enlarged view of the portion 23-23 in FIG. 22; and,
 FIG. 24 is a partial enlarged cross-sectional view taken along the line 24-24 of FIG. 23.
 The portions of the tennis racket frame illustrated in broken lines form no part of the claimed design.
